UNITED STATES PATENT OFFICE

CLARENCE R. CALLAWAY, OF LONG BEACH, NEW YORK, ASSIGNOR TO GURNEY ELEVATOR COMPANY, INC., OF NEW YORK, N. Y., A CORPORATION OF PENNSYLVANIA

ELEVATOR GUIDE RAIL LUBRICATING MECHANISM

Application filed May 22, 1929. Serial No. 364,978.

This invention relates to guide rail lubricating devices for elevator guide rails.

In order to eliminate friction and provide for the smooth and efficient operation of an elevator car and the counterweighting mechanism, it is common to lubricate the guide rails. In one form of lubricating mechanism for this purpose, the mechanism operates continuously and this is undesirable since too much lubricant is fed to the guide rails.

This invention has for its salient object to provide simple, practical and efficient guide rail lubricating mechanism, so constructed and arranged that lubricant will be fed to the guide rails only when the car is running.

Further objects of the invention will appear from the following specification taken in connection with the drawings, which form a part of this application and in which

Fig. 1 is an elevational view of lubricating mechanism constructed in accordance with the invention;

Fig. 2 is a top plan view of the construction shown in Fig. 1;

Fig. 3 is an end elevation of the mechanism illustrated in Fig. 1; and

Fig. 4 is a transverse sectional elevation of a guide rail shown in the connection of the lubricating mechanism thereto.

The invention briefly described consists of a lubricating mechanism operatively connected to the car operating shaft and so constructed and arranged that lubricant will be fed to the guide rails whenever the drive shaft for the car is operated.

Further details of the invention will appear from the following description.

In the particular embodiment of the invention illustrated in the drawings, the car operating shaft is shown at 10 and a stub shaft or spindle 11 is directly connected to and extends beyond the shaft 10.

The lubricating mechanism is mounted in a casing 15 provided with suitable bearings for the shaft 11 and adapted to house the mechanism.

The lubricating mechanism is illustrated in connection with a well known system, including a storage tank 16, accumulator 17, header or distributor 18, and air vent 19.

The oil is pumped by means of a piston pump 20 having a piston rod 21 extending downwardly therefrom and engaging an eccentric 22 mounted on the stub shaft or spindle 11. A drip pan or well 25 is positioned below the eccentric to catch any oil that leaks out around the reciprocating piston rod 21, this oil functioning to lubricate the contact between the piston rod and the eccentric.

The pump 20 receives oil from the reservoir or supply tank 16 through a conduit 26 and discharges oil through a conduit 27 which leads to the air vent 19. The air vent 19 is connected by a conduit 30 to the accumulator 17 and oil passes from the accumulator 17 through a conduit 31 through the header or distributor 18. The oil passes from the distributor through pipes 32, 33, 34 and 35 to rail cups 40. The rail cups, as shown in Fig. 4, surround the rails and are preferably filled with suitable packing material, such as felt packing 41. In Fig. 3 there are shown four conduits from the header leading to the guide rails, it being assumed that there are two guide rails for the car and two guide rails for the counterweighting mechanism. It will be obvious that as many conduits may be provided as there are rails to be lubricated.

In Fig. 3 there is shown a return conduit 45 leading from the accumulator to the supply tank, through which any excess oil is returned to the supply tank.

In the operation of the mechanism above described, the accumulator 17 is initially filled with oil and after the pressure in the accumulator is built up, each stroke of the pump 20 will cause an increment of oil to be fed to the header and through the header to the conduits 32, 33, 34 and 35, which lead to the guide rails. Thus, whenever the car operating shaft is rotating, the pump will be operated and oil will be fed to the guide rails.

Although the drawings illustrate certain specific details of apparatus for carrying out the invention, it should be understood that the invention is not limited to the particular structure shown and described but that changes in the construction and in the arrangement of the various cooperating parts may be made without departing from the

spirit or scope of the invention, as expressed in the following claims.

What I claim is:

- 5 1. Lubricating mechanism for elevator guide rails comprising a pump, a car operating shaft, operative connections between the shaft and pump, guide rails, and conduits for conducting oil from the pump to said rails.
- 10 2. Lubricating mechanism for elevator guide rails comprising a car operating shaft, a pump driven thereby, guide rails, lubricating cups mounted thereon, and conduits leading from the pump to the lubricating cups.
- 15 3. Lubricating mechanism for elevator guide rails comprising a car operating shaft, a shaft adapted to rotate therewith, a pump disposed above said second shaft and driven thereby, guide rails, and conduits for conducting oil from the pump to said rails.
- 20 4. Lubricating mechanism for elevator guide rails comprising a car operating shaft, a shaft adapted to rotate therewith, an eccentric mounted on said last named shaft, a pump disposed above said eccentric and
- 25 having a piston and a piston rod operatively driven by said eccentric, guide rails, and conduits for conducting oil from the pump to said rails.

CLARENCE R. CALLAWAY.
